DESIGN.

W. G. OLDHAM.
CHENILLE FABRIC.

No. 21,271.

Patented Dec. 29, 1891.

UNITED STATES PATENT OFFICE.

WILLIAM G. OLDHAM, OF PHILADELPHIA, PENNSYLVANIA, ASSIGNOR TO
WILLIAM T. SMITH & SON, OF SAME PLACE.

DESIGN FOR A CHENILLE FABRIC.

SPECIFICATION forming part of Design No. 21,271, dated December 29, 1891.

Application filed December 4, 1891. Serial No. 414,057. Term of patent 3½ years.

To all whom it may concern:

Be it known that I, WILLIAM G. OLDHAM, a citizen of the United States, residing at Philadelphia, in the county of Philadelphia and State of Pennsylvania, have invented and produced a new and original Design for a Woven Chenille Fabric, of which the following is a specification, reference being had to the accompanying photographic print, making a part of this specification, and is sufficient to enable one skilled in the art of weav-

ing chenille fabrics to make and use my invention.

What I claim as my invention, and desire to secure by Letters Patent, is—

The design for a woven chenille fabric, consisting of the ornamentations shown in the accompanying photographic print.

W. G. OLDHAM.
